UNITED STATES PATENT OFFICE.

FRED HILTON, OF MANCHESTER, ENGLAND.

COIN-FREED STAMPING MECHANISM.

1,068,240.

Specification of Letters Patent.

Patented July 22, 1913.

Application filed February 12, 1910. Serial No. 543,448.

To all whom it may concern:

Be it known that I, FRED HILTON, a subject of the King of Great Britain and Ireland, and a resident of Manchester, in the county of Lancaster, England, have invented new and useful Coin-Freed Stamping Mechanism, of which the following is a specification.

This invention relates to coin freed mechanism for stamping or franking letters or the like with a postage or other fee in lieu of placing adhesive stamps upon them.

This mechanism is of a type in which the user after insertion of the required coin gives a direct pull to the stamp to effect the impression through the medium of the inserted coin, and is primarily intended for direct access and operation by the public and to be placed at convenient places, as for example at letter boxes.

The mechanism is so constructed that the stamp after stamping a letter or the like (hereinafter referred to as a letter) cannot be moved back or allowed to move back and be again operated for stamping a letter before the payment of another coin, and so that the stamp can be properly and efficiently used for stamping letters of any reasonable variation in thickness. It is preferred, also, that the coin which has last caused or permitted the operation of the mechanism should, immediately the stamping has been effected, come into view by being deposited behind a window or the like in the machine and here remain visible until the next coin has been inserted for the next operation.

The stamp itself may be of any suitable self-inking or other type, such, for example, as that type which, when depressed by a handle, turns over and comes down upon the surface to be stamped, and when released moves upward under spring pressure, again turning over to take ink from the under side of a pad for the next impression. The inscription or figures or equivalent on the face of the stamp to be impressed may be any suitable, and may bear a mark to identify the station at which the impression took place.

The accompanying drawings illustrate a stamping apparatus constructed according to my improvements and such drawings will now be referred to and the construction and operation of the machine described. The casing and other parts of the machine which

form no part of my invention and the construction of which are well known in coin freed machines are omitted from the drawings for the sake of clearness, but it is to be understood that the mechanism is enclosed in a suitable casing provided with an opening to a shoot into which the coin is inserted; with a coin receptacle; with an opening into which the letter to be stamped can be inserted and into which the stamp when operated enters to impress the inserted letter; and with an opening or the like through which the operating handle projects; and that no access to the machine is permitted which would enable it to be fraudulently operated. For outside use the machine should of course be weatherproof.

Figure 1 represents the stamping mechanism in front elevation with the stamp out of operation. Fig. 2 represents the same parts in the same positions in side elevation. Fig. 3 is a view similar to Fig. 2 but shows the parts at the moment an impression has been made and the stamp has returned to the top of its stroke. Fig. 4 shows the coin gripping mechanism during the progress of the downward or impression stroke of the stamp but before the impression is made or completed. Fig. 5 similarly illustrates the same parts as Fig. 4 but at the moment of impression and immediately before the liberation of the coin. Fig. 5^a shows the stamp at the impression moment and when the parts shown in Fig. 5 are in the positions there illustrated. Fig. 6 is a plan view from underneath showing how the stamp enters the opening or slot in which the letter is placed for stamping. Fig. 7 illustrates a device for displaying the coin last used.

Similar letters of reference are used to indicate similar parts where they occur in the different figures.

A is the stamp which has a plate B bearing the desired inscription and which can be moved downward to the position shown in Fig. 5^a to make the required impression and which is returned after the impression is made to the position shown in Fig. 1 for re-inking. During each movement the stamp plate turns around a shaft C carried by the frame D which is moved down to make the impression and is returned to its higher position by the spring E when the stamping pressure is taken off. Such a stamp is by itself well known and needs no detailed description here. Attached to

the frame D is the vertical member F having ratchet teeth formed along one edge. It is evident that as this ratchet member is pressed down or released the stamp will be moved down to its impression point or returned.

G is a vertically sliding operating handle bar mounted parallel to and near to the member F and having at its lower end an operating handle G¹ which projects through the machine casing for the user to grasp. Such operating bar can be pulled downward against the pressure of a spring G² which will return the bar G to its highest position when the handle is released. The upper part of the operating bar carries two hooked limbs H H¹ one or both of which is or are hinged and spring controlled. In the example shown in the drawings one only of the limbs H is hinged as shown and the two limbs are normally held in their closest relative positions by a spring H². When in their closest relative positions (illustrated in Figs. 2, 3 and 4) the hooked limbs have a distance between them which is less than the diameter of the coin with which they are to be used, but are farther apart than the width of the ratchet member F toward which they project. The upper part of the ratchet member carries a stud or projecting part F¹ which comes below the hooks H H¹ and is sufficiently below such hooks when the machine is ready for the insertion of a coin as to permit such coin to stand on its edge upon the projection and below the hooks.

With the different parts in the positions shown in Figs. 1 and 2 the person desirous of using the mechanism places the coin in the machine through the shoot J. The coin comes to rest on its edge on the projection F¹ as shown at K in Figs. 1 and 2. The user then places the letter L to be stamped properly in the slot M below the stamp and pulls down the handle G¹. As the handle is pulled downward the hooks H H¹ come over and engage with the edge of the coin or check and exert their pull through such coin down on to the ratchet member F and the attached stamp until the stamp comes down on to the surface of the letter (see Fig. 5^a). The spring H² is strong enough to prevent the jaw H opening during this part of the movement although not strong enough to prevent it opening when the pressure requisite to give a proper impression is exerted.

Fig. 4 illustrates the positions of the various parts when the stamp has reached the letter and before the hook has begun to open, and Fig. 5 illustrates the position taken up by the movable jaw as it is opening and just about to release the coin owing to the further downward pull on the handle to give a proper impression. As the im-

pression is made the jaws pass down over the coin, and the coin falls away in the direction of the arrow. Up to this moment the ratchet teeth on the edge of the member F have been engaged by a pawl N mounted upon any suitable stationary part of the apparatus, as for example upon the plate O, and as long as such engagement takes place the member F and the attached stamp could not be returned toward the inking position. This ratchet and pawl is adapted to prevent any possibility of the stamp being used to effect a light impression without the jaws giving way, and then being again used for further impressions after a slight return of the ratchet member without the coin being expelled and the mechanism being rendered non-operative. It is intended that the strength of the spring shall be sufficient to cause the jaws to engage the coin until the pull required to give an impression is given to the handle, and that as soon as such required pull is given or as soon as the requisite printing impression is exerted the jaws shall give way and release the coin and thus render the machine inoperative until another coin is inserted. It is preferred however to use the ratchet and pawl although it may be dispensed with.

The impression having been made and the coin having fallen from the projection F¹ it becomes necessary that the stamp shall at once return to its inking and inoperative position and to permit this the pawl (when used) must be released from the ratchet. This can be accomplished in either or both of two ways as shown in the drawings. After the jaws H H¹ have passed over and released the coin, the handle G¹ (owing to the resistance to its movement being gradually lessened) will be pulled suddenly farther downward until the jaw H¹ comes into contact with and depresses the pawl N thus releasing the ratchet member, which then at once with the stamp flies upward under the pressure of its spring E. Or the release of the pawl may be accomplished before the coin removes from the projection F¹ by the hinged jaw H, as it is opening, coming by means of a projection against the tail N¹ of the pawl. The ratchet member F is thus free to fly up with the stamp as soon as the coin gets out of its way, and the further downward movement of the jaw H¹ and its engagement with the pawl insures the pawl remaining in its inoperative position during the ascent of the ratchet member. To insure the operations being properly performed it is preferred to so arrange the parts that the handle bar rings a bell or otherwise gives a signal when it has performed all its functions, and that the instructions to the user shall direct him to pull down the handle until

such signal is given. If the pawl and ratchet are not used the stamp will, of course, fly back as soon as the coin is released. The handle is then released by the user and is returned by its spring G^2 to its inoperative position. All is now ready for a further operation upon the insertion of another coin. It is evident that with no coin inserted the handle can only be idly pulled up and down as there is nothing for the jaws to engage with to operate the stamp. It is also evident that letters of varying thicknesses can be efficiently stamped by the mechanism described as the necessary pressure to release the coin is not exerted until the stamp reaches the letter, and that the pressure to release the coin will be exerted whenever the stamp does reach the letter and the pull on the handle is continued. If desired however the pad of the stamp may be spring mounted.

To act as a deterrent to fraud by the use of valueless disks in lieu of coins it is preferred that the last coin used shall remain on view until the next operation of the machine. This may be effected by the use of the appliances shown in Fig. 7. The coin K after it leaves the jaws and ratchet member and falls, is guided into the left upper compartment P of a light wheel Q which rotates a quarter of a turn under the impact and weight of the coin and permits the further fall downward of the coin on to a hinged pan R which, at the moment the coin is delivered to it by the wheel past the curved screen W is held by a sufficient counterweight in the closed position against the casing wall. Immediately above the pan is a window S through which the coin resting upon it is visible from outside the machine. As another coin falls into the wheel and gives it a quarter turn, the four leaved cam T on the shaft U of the wheel Q operates to move the pan to the position indicated in dotted lines through the medium of the arm V attached to the pan pivot and thus permit the coin previously supported by the pan to fall into a receptacle. As the rotation of the wheel continues to gently deliver the coin which is turning it to the tray the pan again closes under the combined action of its counterweight and the cam to support the thus delivered coin.

If desired any suitable counting device may be combined with the apparatus to record the number of times it has been used, and be operated by the reciprocations of the stamp or some part attached to or moving therewith.

The slot M into which the letters are inserted for stamping is preferably large enough to permit the letter to be moved therein for two or more impressions to be

made side by side on one letter, and stamps of various values and all constructed as herein described may be combined together in one machine.

I claim:—

1. In check controlled operating means, a movable operating part, a reciprocable rod for operating such part, an abutment on such rod for the reception of the check standing on its edge, a chute leading to such abutment, two spring controlled hooked limbs adapted to engage the check on its upper edge, and a handle carrying and operating such hooked limbs whereby a downward movement will be imparted to said operating part through the inserted check, substantially as described. 70

2. In check controlled operating means, a movable operating part, a reciprocable rod for operating such part, an abutment on such rod for the reception of the check standing on its edge, a chute leading to such abutment, two hooked limbs pivotally connected and adapted to engage the check at its upper edge, a spring normally holding the limbs in their closest relative position, and a handle operating and carrying such hooked limbs whereby a downward movement will be imparted to said operating part through the inserted check and the check will be released when the operating part has been actuated, substantially as described. 85

3. In check controlled operating means, a movable operating part, a reciprocable rod for operating such part, an abutment on such rod for the reception of the check standing on its edge, a chute leading to such abutment, two hooked limbs pivotally connected and adapted to engage the check at its upper edge, a spring normally holding the limbs in their closest relative position, a handle carrying and operating such hooked limbs whereby a downward movement will be imparted through the inserted check to the rod operating the first mentioned part, a rack on such rod, a detent engaging with such rack whereby the undesired return of said operating part will be prevented but which is disengaged by the rear end of a hooked limb coming in contact with an extension of the detent, substantially as described. 100

4. In check controlled operating means, a movable operating part, a reciprocable rod for operating such part, an abutment on such rod for the reception of the check standing on its edge, a chute leading to such abutment, two hooked limbs pivotally connected and adapted to engage the check on its upper edge, a spring normally holding the limbs in their closest relative position, a handle carrying and operating such hooked limbs whereby a downward movement will be imparted through the inserted check to the rod operating the first mentioned part, a 115

4

rack on such rod, a detent engaging with such rack whereby the undesired return of the operating part will be prevented but which is disengaged by the rear end of a 5 hooked limb coming in contact with an extension of the detent, and a wheel divided into compartments into which the check falls rotating it a quarter turn and dropping the check on to a hinged pan for exhibiting 10 the last check used through a window, the

15 said pan being operated from a cam on the wheel shaft to permit the check to fall into a receptacle, substantially as described.

In witness whereof I have hereunto set my hand in the presence of two subscribing witness- 15

FRED HILTON.
